This invention relates to new and useful improvements in blanket shelves for beds and the primary object of the present invention is to provide a device that is interposed between a bed mattress and bed springs to conveniently support a blanket, comfort or the like.

UNITED STATES PATENT OFFICE

2,562,333

BLANKET SHELF FOR BEDS

Irene W. Ries, Sandusky, Ohio

Application September 5, 1947, Serial No. 772,305

5 Claims. (Cl. 5—318)

1. This invention relates to new and useful im-

provements in blanket shelves for beds and the primary object of the present invention is to provide a device that is interposed between a bed mattress and bed springs to conveniently support a blanket, comfort or the like.

Another important object of the present invention is to provide a blanket shelf for beds slidably mounted in a frame for selective adjustment to accommodate various sizes of blankets, comforts or the like in a neat and attractive manner.

A further object of the present invention is to provide a shelf for beds including means for guiding and limiting the longitudinal movement of the shelf relative to one end of the bed.

A still further aim of the present invention is to provide a blanket shelf for beds that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of a bed, the present invention applied thereto for use;

Figure 2 is a side elevational view of the present invention showing the shelf portion in a partially extended position, and with parts of the guide frame broken and shown in section; and,

Figure 3 is a perspective view of the present invention showing the shelf in a partially extended position.

Referring now to the drawings in detail, wherein for the purpose of illustration, there is disclosed a preferred embodiment of the present invention, the numeral 10 represents a guide frame of the present invention generally, comprising a pair of outer substantially flat rectangular sections 12, and an intermediate section 14 interposed between sections 12. These sections 12 and 14 are preferably of a plastic material.

A longitudinal slot 16 is provided in the intermediate section 14 at one end to slidably engage a plastic shelf or flat panel 18.

Projecting outwardly from substantially the center of one face of shelf 18, is a guide lug 20 that slidably engages a longitudinal slot 22 provided in one of the outer sections for guiding the longitudinal movement of the outer section rela-

2. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

3. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

4. The combination of claim 3 wherein said guide means includes a longitudinal slot pro-

5. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

6. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

7. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

8. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

9. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

10. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

11. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

12. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

13. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

14. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

15. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

16. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

17. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

18. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

19. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

20. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

21. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

22. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

23. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

24. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

25. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

26. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

27. A blanket shelf for beds comprising a frame interposed between a mattress and a bed spring and having a longitudinal slot, a shelf slidably mounted in said slot, and means for guiding the movement of said shelf relative to said frame, said shelf including a transverse retaining board at one end disposed perpendicular to said shelf.

28. A blanket shelf for beds comprising a frame having three superimposed sections including upper and lower outer sections and an intermediate section interposed between the upper and lower sections, a longitudinal slot provided in the intermediate section, a shelf slidably mounted in the slot, and means for guiding the longitudinal movement of the shelf relative to the frame.

vided in one of said outer sections and a guide lug carried by said shelf slidably received in the slot in said outer section, said lug having a rounded top projecting above the outer surface of the upper section.

4. In combination with a mattress and a bed spring, a blanket shelf for beds comprising a pair of U-shaped members, spacing means between said members, a shelf slidably mounted between said members, and means guiding the sliding movement of said shelf, said members being inserted between the mattress and the bed spring at the foot end of the mattress and the bed spring.

5. In combination with a bed construction having a mattress and a spring; a blanket shelf comprising a frame slipped between the mattress and spring at one end of the mattress and the spring and held between the mattress and the spring by the weight of the mattress, said frame 20 having a pair of spaced portions, a shelf slid-

ably received between said portions and spaced from the mattress and spring for unrestricted sliding movement, and a wall extending upwardly from said shelf forming a retaining wall

5 for a blanket positioned on the shelf when the latter is extended from the frame.
